UNITED STATES PATENT OFFICE

SAMUEL M. J. JACOBS, OF NEW YORK, N. Y.

DESIGN FOR A COMBINED KNIFE AND CIGAR BOX OPENER

Application filed May 6, 1929. Serial No. 31,110. Term of patent 14 years.

To all whom it may concern:

Be it known that I, SAMUEL M. J. JACOBS, a citizen of the United States, residing at New York, in the county of New York and State of New York, have invented a new, original, and ornamental Design for a Combined Knife and Cigar Box Opener, of which the following is a specification, reference being had to the accompanying drawing, forming part thereof.

Figure 1 is a top plan view, and Figures 2 and 3 are a side elevation and bottom view, respectively, of a combined knife and cigar box opener showing my new design.

I claim:

The ornamental design for a combined knife and cigar box opener, as shown.

SAMUEL M. J. JACOBS.
